GAS BURNER ASSEMBLY

Alick Clarkson, Itasca, Ill., assignor of one-half to Vapor Heating Corporation, Chicago, Ill., a corporation of Delaware

Application March 15, 1948, Serial No. 14,951

9 Claims. (Cl. 158—7)

1

This invention relates to improvements in a gas burner assembly suitable for use as a heat generating unit for gas fired heat-exchangers of various constructions including steam and hot water boilers of the water-tube type.

A principal object of the invention is to provide an improved gas burner assembly which is so constructed as to effect efficient burning of a large volume of gaseous fuel in a relatively small combustion chamber.

The invention may be described briefly as comprising a fire ring A and a fuel nozzle structure B surrounding the same which are positioned within an air pressure chamber C in a position to direct the products of combustion downwardly into the boiler D. A cylindrical member E defining a combustion chamber is supported above the ring A and fuel nozzle with the lower end of the cylinder E being spaced from the upper edge of the fire ring A so as to provide an air passage F communicating with the air chamber C. The cylindrical member E is supported at its upper end within an air dome G which dome is also in communication with the air chamber C. A pilot nozzle H extends into the upper portion of the combustion chamber so as to direct a pilot flame downwardly therein. The said nozzle communicates through air passage I with the said air pressure chamber C.

Gaseous fuel from nozzle structure B, together with a circular sheet of combustion air, is delivered upwardly into the combustion chamber along the circular wall thereof. Secondary air is delivered into the upper central portion of the combustion chamber and moves downwardly within the upwardly moving flame. The central core of air, under pressure, moving in opposition to the surrounding sheet of gas and air, mixes with the burning gaseous mixture and imparts toroidal movement to the burning mixture. The high turbulence maintained in the combustion chamber and the vertical looped path or toroidal movement of the flame and partially ignited fuel brings the partially ignited fuel into repeated mixing engagement with additional air and thereby insures complete combustion of the fuel as it moves in its circuitous course from the combustion chamber into the boiler D. The said combustion air is highly heated because of the arrangement of the combustion chamber within the air chamber C and thereby increases the efficiency of combustion.

A pilot nozzle H, for directing a pilot flame downwardly into the combustion chamber, ex-

2

tends into the upper portion of the chamber at one side of the vertical center thereof so as to insure contact of the pilot flame with the combustible products at all times. The said pilot nozzle, during high flame operation of the burner, receives air under pressure through the passage I so that the pilot flame assumes a long pencil-like character. However, when the gas and air pressure is shut off from the main burner 10 the pilot flame is reduced in length, but will remain lighted in readiness for renewed high flame operation. During the inactive period of the burner, a weighted valve J in the air passage I drops to its dotted line position so as 15 to admit outside air to be drawn into the passage I by the inspirating action of the gas jet K and thereby provides sufficient air to support combustion at the discharge end of the pilot nozzle. However, as soon as renewed normal operation is resumed the air pressure in chamber C enters the passage I and thereby closes the weighted valve J.

The hot products of combustion from the chamber E move downwardly through the fire ring A and pass through the heating coils of the boiler into the space L, between the coils and the outer casing M, and are discharged through the smoke box N to a suitable smoke stack not shown.

30 Another object of the invention is to provide an improved gas burner assembly constructed and adapted to operate in the manner hereinabove briefly described.

Another object is to provide, in a gas burner 35 of the above character, an improved construction whereby the combustion air is preheated to a high degree and introduced into the combustion chamber at locations to create high turbulence within the combustion chamber and thereby insure thorough mixing of the gaseous fuel and air.

Another object is to provide a construction 40 in which the combustion air is utilized to prevent overheating of the walls of the combustion chamber.

Another object is to provide, in a gas burner of the above character, a long pencil-like pilot flame which is projected downwardly into the combustion chamber at a location spaced from 45 the vertical center thereof so as to insure ignition of the gaseous fuel.

Another object is to provide air control means for the pilot flame, whereby air under pressure is supplied to the pilot nozzle during high flame 50 operation of the burner and whereby a reduced

quantity of air is supplied to the pilot nozzle during inactive periods of the main burner.

A further object is to provide improved arrangements and constructions which facilitate ready assembly of the several parts and which facilitate ready dismantling of the structure when it is necessary or desirable to repair or replace parts thereof.

The invention is illustrated in the accompanying drawings wherein:

Fig. 1 is a vertical section showing a gas burner assembly constructed in accordance with this invention supported on the upper portion of a water-tube boiler.

Fig. 2 is a plan view of the burner structure shown in Fig. 1.

Fig. 3 is a fragmentary sectional view taken on line 3—3 of Fig. 2 to illustrate the manner in which the gaseous fuel is delivered to the fuel nozzle, and

Fig. 4 is a fragmentary view in side elevation illustrating a valve holding means for holding a manually adjusted valve in a desired predetermined position.

Referring now to Fig. 1 of the drawings: The gas burner assembly, as previously indicated, is suitable for use in connection with steam generators and hot water boilers of various constructions. It will be understood therefore that the specific form of steam generator herein shown is for purpose of illustration and is not intended as a limitation on the scope of use of the invention disclosed.

The generator D comprises a plurality of substantially helical pipe coils 10, 11, 12, 13 and 14 arranged co-axially about the central vertical axis of the generator. The several coils are arranged so that the loops of one coil assume a staggered relation to adjacent coils, as shown in Fig. 1, so that the hot gases delivered through the fire ring A and into the heat space of the generator will pass between the coils of the generator and thereby take a sinuous path through the several banks of heating coils. This arrangement of the heating coils in staggered relation insures maximum surface contact of the hot gases with the coils. The gases of combustion after passing between the coils of the generator enter the space L and thereafter pass through the smoke-box N and flue opening O.

The burner assembly includes an air chamber C which, in the present embodiment, is of circular configuration and provides a closure for the annular space L of the steam generator D. The said air casing is provided with a partition 15 which separates the casing into the said air chamber C and a smoke-box N. The said partition 15, as viewed in plan (Fig. 2), provides a crescent shaped smoke-box to facilitate ready discharge of the spent products of combustion after they pass through the coils of the heat-exchanger. The smoke-box N is provided with flue opening O which may be connected to a suitable vent for carrying away the products of combustion. By positioning the partition 15 in the manner indicated so as to separate the air chamber from the smoke-box, the exhaust products entering the smoke-box serve, to some extent, to apply heat to said partition 15 and thereby heat a portion of the air contained in chamber C.

The fire ring A is preferably composed of molded refractory material 16 and is positioned at a location for directing the hot combustion gases into the heating space of the generator D.

In the present case, since the generator D is formed to operate on a down draft principle, the fire ring 16 is positioned on the upper end of the water coils of the generator. In order to support the said ring in proper position, a conical base member 17 seats on the coils of the generator so as to provide a flat surface for the base portion of the ring 16. The fire ring extends into the air chamber C and the open upper end of the ring is flared outwardly as shown at 18 so as to provide a conical configuration in cross section. The upper edge portion of the said fire ring is provided with an upwardly outwardly inclined metallic flange 19 which serves as an air deflector in the manner hereinafter described. A main fuel nozzle B surrounds the fire ring A and is provided with a plurality of upwardly projecting jet elements 20 arranged in spaced relation to each other and positioned to discharge a gaseous fuel upwardly into the combustion chamber, the gaseous fuel being delivered to the main fuel nozzle through a supply pipe 21 and downwardly inclined connection 22, as shown in Fig. 3 of the drawings.

The combustion chamber is defined by a cylindrical casing E which is suspended at its upper end from an air dome structure G. The lower edge portion 23 of the casing E is flared outwardly so as to direct air from the chamber C into the passage F around the several jet elements 20. The upwardly and outwardly inclined flange 19 of the fire ring serves to deflect the air in passage F in a direction toward the circular side wall of the combustion chamber at a location adjacent to the discharge ends of the jet elements 20 and thereby insure thorough initial mixing of the air and gaseous fuel as it enters the combustion chamber. This mixture of gaseous fuel and air is directed upwardly into the combustion chamber along the vertical wall thereof and is thereafter mixed with air introduced into the combustion chamber at the upper end thereof. The upper end of the combustion chamber casing is in the form of a truncated cone 24 which functions as a baffle for directing the upwardly moving gaseous mixture inwardly toward the center of the combustion chamber where it is mixed with the air introduced into the upper end portion of the combustion chamber. The said upper end 24 of the combustion chamber is secured to a cap plate 25 of similar truncated cone form, but is spaced from the under surface thereof by means of spacers 26 so as to provide an air passage 27 for directing air upwardly over the top sheet 24 of the combustion chamber and into the upper portion of the chamber through the central opening 28. The said cap plate is connected by means of a cylindrical portion 29 to the inner surface of the top portion of a casing 30 defining the air dome G. A manually adjustable sleeve valve 31 surrounds the cylindrical portion 29 and is provided with openings 32 adapted to be moved into register with corresponding openings 33 in the said cylindrical portion 29. The sleeve valve is held in its suitably adjusted position by means of wing nuts 34—34 which engage bolts extending up through elongated slots 35—35 in the top portion of the air dome G.

The cap sheet 25 is preferably formed so that its lower edge extends into the air passage 36 between the vertical wall structure of the combustion chamber and the vertical wall structure 37 of the air dome G, so as to direct a major portion of the air from passage 36 into the passage

27 and thence into the upper end of the combustion chamber. However, a substantial portion of air passes around the lower edge of the cap sheet 25 and enters the cylindrical portion 29 through the sleeve valve controlled openings 33. It is by means of the sleeve valve 31 that the amount of air delivered into the upper end of the combustion chamber may be varied to suit the prevailing operating conditions. The lower edge portion of the air dome G is formed with an angular flange 38 which is removably secured to a ring element 39 which forms a part of the air chamber casing. It will be seen, therefore, that the air dome G and the combustion chamber casing E may be readily and conveniently removed from the air chamber casing when it is desired to repair or renew the fire ring 16 or main fuel nozzle B.

The gaseous fuel introduced into the combustion chamber is ignited by means of a pilot flame 40. The pilot flame 40 is maintained by a mixture of gas and air which is discharged from the pilot nozzle H. This nozzle is of known construction and extends into the combustion chamber through a plate 41 which is removably secured to and forms the top plate of the air dome G. When the apparatus is operating with fuel delivered from the main fuel nozzle B air, under pressure, is delivered to the pilot nozzle through the passage I so that the fuel and air mixture will be discharged into the combustion chamber with considerable velocity from the pilot nozzle H and thereby form a relatively long pencil-like flame for maintaining the gaseous mixture ignited within the combustion chamber. The amount of pressure air supplied to the pilot nozzle may be controlled by adjusting a valve 42 positioned in said passage I. The said valve 42 is held in its adjusted position by means of a ratchet bar 43 positioned to engage the operating arm 44 of the said valve 42. When the operation of the main fuel nozzle B is discontinued the air pressure is relieved and the pilot flame is reduced in length but it remains lighted so as to be available for high flame operation of the main fuel nozzle B. During the inactive period of the main fuel nozzle B the weighted valve J assumes the position indicated in dotted lines in Fig. 1 so as to admit outside air into the passage I through an opening 45, the air being drawn through said opening by the inspirating action of the gas discharged from the jet K into the supply tube 46 leading to the pilot nozzle H.

Summary of operation

When the burner assembly is initially put into operation, gas is delivered through jet K into the supply tube 46 of the pilot nozzle H. During this initial operation, the valve J is in the dotted line position indicated in Fig. 1. Consequently, external air is drawn through opening 45 by the inspirating action of the jet K to provide the initial mixture for the pilot flame. This initial mixture is ignited by means of an electrical discharge between the lower ends of a pair of electrodes 47—48. This electrical ignition is operated only normally during the initial starting of the burner, since the pilot flame, when once ignited, thereafter serves to ignite the fuel discharged from the main fuel nozzle.

During normal operation of the burner gas is delivered from the jet elements 20 of the main fuel nozzle so as to flow upwardly along the vertical wall of the cylindrical combustion chamber. Primary combustion air is delivered upwardly

through the passage F so as to mix with the gas from the nozzle elements 20 and flow upwardly along the vertical wall of the combustion chamber. Additional air from the air chamber C moves upwardly along the outer surface of the combustion chamber E so as to become heated and is directed, in the form of a blanket of air, through the passage 27 overlying the top sheet 24 of the combustion chamber and also through the valved openings 33 in the cylindrical portion 29. This air creates turbulence in the combustion chamber and moves downwardly in the form of a turbulent stream. It engages and mixes with the mixture of gas and air which is deflected inwardly by the top sheet 24 of the combustion chamber and thereby imparts to the gaseous mixture a series of vertical loop movements. The series of vertical loops formed by the flame and partially burned fuel causes the partially burned gases to be brought into contact with additional air sufficient to support complete combustion. The hot products of combustion are then moved downwardly through the fire ring A, thereby heating the ring and insuring combustion of any gaseous fuel at this location. The said products continue downwardly into the heating space defined by the inner coils 10 of the generator D and pass through the circuitous passages defined by the staggered arrangement of the several coils 10, 11, 12, 13 and 14 of the heat-exchanger D. The products in and around the several coils and giving up heat thereto enter the space L intermediate the coils and the outer casing M and are discharged through the flue opening O.

I claim:

1. A gas burner assembly for delivering hot gases of combustion into a heat-exchange apparatus and comprising a casing defining a chamber for containing air under pressure; a cylindrical casing defining a combustion chamber having an end wall at one end and open at the other end and having its open end extending into said air chamber, whereby air enters the combustion chamber through said open end and whereby the cylindrical wall of the combustion chamber transfers heat to the air within said air chamber; a main fuel nozzle for delivering gaseous fuel into the combustion chamber adjacent the cylindrical wall thereof through said open end of the combustion chamber casing; an air dome surrounding the end portion of the combustion chamber casing having said end wall, but spaced therefrom to provide an air passage communicating with said air chamber; an annular cap plate overlying the said end wall of the combustion chamber casing and providing a passage for directing air under pressure into the combustion chamber through an opening in said end wall, whereby the last mentioned air mixes thoroughly with the gaseous fuel and imparts toroidal movements thereto; a cylindrical portion uniting the central portion of said cap plate with the air dome and provided with openings defining air passages for delivering additional air into the combustion chamber; and valve means for varying the amount of air delivered through the last mentioned passages into the combustion chamber.

2. A gas burner assembly for delivering hot gases of combustion into a heat-exchange apparatus and comprising a casing defining a chamber for containing air under pressure; a cylindrical casing defining a vertical combustion chamber having an open lower end extending into said air chamber, whereby the air enters

the combustion chamber through said lower end; means providing an upper end wall for said combustion chamber and having a central opening therein; a main fuel nozzle for delivering gaseous fuel into said combustion chamber through said open lower end of the combustion chamber casing; means for removably supporting the combustion chamber from the upper portion of said air chamber casing and defining an air passage for directing air under pressure from said air chamber into the upper end of said combustion chamber through said central opening, whereby the last mentioned air mixes with the gaseous fuel and imparts vertical whirling movements thereto; and means for directing a pilot flame into the upper portion of the combustion chamber to ignite the fuel and air therein.

3. A gas burner assembly for delivering hot gases of combustion into a heat-exchange apparatus and comprising a casing defining a chamber for containing air under pressure; a cylindrical casing defining a vertical combustion chamber open at one end and having its open end extending into said air chamber, to admit air from said air chamber into said combustion chamber; a main fuel nozzle for delivering gaseous fuel into the combustion chamber through said open end thereof; means communicating with the said air chamber for directing air under pressure into the upper end of said combustion chamber, whereby the last mentioned air mixes with the gaseous fuel and imparts vertical whirling movements thereto; a fire ring for directing the hot combustion gases from the combustion chamber into the heat-exchange apparatus; a partition in the said air chamber extending partially around the combustion chamber casing and defining a smoke-box for receiving the spent gases of combustion from the heat-exchange apparatus.

4. A gas burner assembly for delivering hot gases of combustion into a heat-exchange apparatus and comprising a casing defining a chamber for containing air under pressure; a cylindrical casing defining a vertical combustion chamber open at its lower end and having its open end extending into said air chamber to admit air from said air chamber into the combustion chamber; a main fuel nozzle for delivering gaseous fuel into the said combustion chamber through said open end thereof; means communicating with said chamber for directing air under pressure into the upper end of said combustion chamber, whereby the last mentioned air mixes with the gaseous fuel and imparts vertical whirling movements thereto; a pilot nozzle extending into the upper portion of the combustion chamber for delivering a pilot flame downwardly therein to ignite said gaseous fuel, a fuel jet element for delivering gas into the pilot nozzle; means defining an air passage communicating with said air chamber for directing air under pressure to said pilot nozzle; and a manually adjustable valve for varying the amount of the last mentioned air.

5. A gas burner assembly for delivering hot gases of combustion into a heat-exchange apparatus and comprising a casing defining a chamber for containing air under pressure; a cylindrical casing defining a vertical combustion chamber open at its lower end and having its open end extending into said air chamber to admit air from said air chamber into the combustion chamber; a main fuel nozzle for delivering gaseous fuel into the said combustion

chamber through said open end thereof; means communicating with said chamber for directing air under pressure into the upper end of said combustion chamber, whereby the last mentioned air mixes with the gaseous fuel and imparts vertical whirling movements thereto; a pilot nozzle extending into the upper portion of the combustion chamber for delivering a pilot flame downwardly therein to ignite said gaseous fuel, a fuel jet element for delivering gas into the pilot nozzle; means defining an air passage communicating with said air chamber for directing air under pressure to said pilot nozzle and having also an air port therein for admitting atmospheric air into the last mentioned passage; a pressure actuated valve positioned in said air passage and adapted to open to admit said atmospheric air when the air pressure within said passage falls below a predetermined point, whereby the pilot flame is supplied with combustion air drawn into the passage through said port by the inspirating action of the fuel jet delivered into said pilot nozzle.

6. A gas burner assembly for delivering hot gases of combustion into a heat-exchange apparatus and comprising a casing defining a chamber for containing air under pressure; a cylindrical casing defining a combustion chamber open at one end and having its open end extending into said air chamber, whereby the cylindrical wall of the combustion chamber transfers heat to the air within said air chamber; a fire ring arranged concentric to the axis of the combustion chamber and extending into said air chamber and into said open end of the combustion chamber to deliver the hot combustion gases from the burner into the heat-exchange apparatus and defining the inner perimeter of an annular passage for delivering an annular stream of air into the combustion chamber through the open end thereof; a main fuel nozzle surrounding said fire ring for delivering gaseous fuel into the combustion chamber through said annular air passage; means communicating with said air chamber and with the other end of the combustion chamber for directing air under pressure into the combustion chamber in a direction opposite to the air delivered through said annular passage, whereby the said air under pressure mixes with the annular stream of air and gaseous fuel and imparts toroidal movements thereto; and a pilot nozzle extending into the combustion chamber for delivering a pilot flame therein to ignite said fuel and air.

7. A gas burner assembly for delivering hot gases of combustion into a heat-exchange apparatus and comprising a casing defining a chamber for containing air under pressure; a cylindrical casing defining a vertical combustion chamber open at its lower end and having its open end extending into said air chamber, whereby air enters the combustion chamber through said open end and whereby the cylindrical wall of the combustion chamber transfers heat to the air within said air chamber; a main fuel nozzle in the form of a ring for delivering gaseous fuel into the combustion chamber adjacent the cylindrical wall thereof through said open end of the combustion chamber casing; an air dome surrounding the upper portion of said combustion chamber casing and communicating with said air chamber and with the other end of the combustion chamber for directing air under pressure into the combustion chamber in a di-

reaction opposite to the air and gaseous fuel delivered through the open end thereof, whereby the last mentioned air mixes with the gaseous fuel and imparts toroidal movements thereto; and a pilot nozzle extending into the combustion chamber for delivering a pilot flame therein to ignite said fuel and air.

8. A gas burner assembly for delivering hot gases of combustion into a heat-exchange apparatus and comprising a casing defining a chamber for containing air under pressure; a cylindrical casing defining a combustion chamber having an end wall at one end and open at the other end and having its open end extending into said air chamber, whereby air enters the combustion chamber through said open end and whereby the cylindrical wall of the combustion chamber transfers heat to the air within said chamber; a main fuel nozzle formed with a series of discharge openings disposed in circular arrangement for delivering gaseous fuel into the combustion chamber through said open end of the combustion chamber casing; an air dome surrounding the upper portion of the combustion chamber casing having said end wall, but spaced therefrom to provide an air passage communicating with said air chamber; means defining a central opening in said end wall of the combustion chamber; an annular cap plate overlying the top portion of the combustion chamber casing and providing a passage for directing air under pressure through said central opening into the combustion chamber, whereby the last mentioned air mixes thoroughly with the gaseous fuel and imparts toroidal movements thereto; and a pilot nozzle extending into the combustion chamber for delivering a pilot flame therein to ignite said fuel and air.

9. A gas burner assembly for delivering hot gases of combustion into a heat-exchange apparatus and comprising a casing defining a chamber for containing air under pressure; a cylindrical casing defining a combustion cham-

ber open at one end and having its open end extending into said air chamber, whereby air enters the combustion chamber through the said open end and whereby the cylindrical wall of the combustion chamber transfers heat to the air within said air chamber; a fire ring of molded refractory material extending into said air chamber and into said open end of the combustion chamber to deliver the hot combustion gases from the burner into the heat-exchange apparatus; a main fuel nozzle surrounding the said fire ring for delivering gaseous fuel into the combustion chamber through said open end of the combustion chamber casing; means defining a central air passage leading into the other end of the combustion chamber; means communicating with said air chamber for directing air under pressure into the combustion chamber through said central air passage, whereby the last mentioned air mixes with the gaseous fuel and imparts toroidal movements thereto, and means extending into the upper portion of the combustion chamber for igniting the mixture of fuel and air therein.
